FRANK B. STRICKLER, OF JANEVILLE, WISCONSIN.

CATTLE-STANCHION.

1,199,736.

Specification of Letters Patent. Patented Sept. 26, 1916.

Application filed April 15, 1915. Serial No. 21,517.

To all whom it may concern:

Be it known that I, FRANK B. STRICKLER, a citizen of the United States, and a resident of Janesville, in the county of Rock 5 and State of Wisconsin, have invented certain new and useful Improvements in Cattle-Stanchions, of which the following is a specification.

My invention relates to cattle stanchions 10 and the object is to produce an improved stanchion which is strong and durable and adjustable for cattle of different sizes and which has improved latch mechanism for releasing the stanchion from either side 15 without the necessity of walking from one side of the animal to the other.

My invention is clearly illustrated on the accompanying drawing in which—

Figure 1 is a front view of the stanchion 20 in closed position with parts broken away, Fig. 2 is a similar view showing the stanchion opened, Fig. 3 is a sectional view on plane 3—3, Fig. 1, and Fig. 4 is a sectional view on plane 4—4, Fig. 1.

25 The stanchion comprises two side structures A and B and the upper and lower cross structures C and D. As best shown in Fig. 3, each side structure comprises a metallic bar 5 preferably a length of channel iron, 30 and a lining bar 6 preferably of wood. The bars 5 are arranged with their bases on the inside and are smoothed and rounded in order, that if desired, they may be used without the wood lining. The side structure A 35 is secured to the upper and lower cross structures by upper and lower brackets 7 and 8, the side structure being secured to the brackets by means of bolts or rivets 9 and 10, the upper bracket having side plates 11 and 12 and the lower bracket having similar 40 side plates 13 and 14, the plates of the top bracket receiving between them the end of the upper cross structure C and the side plates of the lower bracket receiving between 45 them the corresponding end of the lower cross structure D. The other side member B is pivoted at its lower end to the lower cross structure D by means of a pivot pin 15 and is adapted to swing and has latching engagement with the upper cross structure C in a manner to be presently described.

Describing now the cross members, the lower cross member is of general rectangular shape and comprises the similar side castings 16 and 17 which have spacing lugs 18 extending therefrom toward each other for

receiving a rivet or bolt 19 for securing the castings together to form the cross member at the end at which the side member B is pivoted. Between the side castings the 60 lower end of the side bar 5 of side structure A is extended and serves to space the castings apart and a locking bolt 20 extends through the side castings and flanges of the bar. It is, however, preferable to make the 65 stanchion adjustable for cattle of different sizes and provision is therefore made to shift the side structure A laterally with reference to the side structure B to increase or decrease the size of the stanchion opening. As shown, the bracket structures 7 and 8 have adjustable engagement with the upper and lower cross structures. The side castings of the lower cross structure have the longitudinal slots 21 and 22 over which 70 the side plates 13 and 14 of the lower bracket 8 engage and the bolt 20 passes through these side plates and the slots 21 and 22, and other bolts 23 and 24 extend through the respective plates and slots as 75 clearly indicated on the drawing. By loosening the nuts on the bolts the lower end of the side structure A can be shifted longitudinally on the lower cross structure and can be secured in any desired position by retightening the nuts. The upper end of the side structure A is similarly adjustable. This upper cross member comprises the side castings 25 and 26 having the longitudinal slots 27 and 28 through which and the side 80 plates 11 and 12 of the upper bracket structure 7 bolts 29 and 30 extend. The ends of the side castings 25 and 26 adjacent bracket 7 extend toward each other and are secured together by a bolt 31. At the center of the 85 lower edges of the side castings are spacing projections 32 and 33 and where desired other spacing extensions 34 may be provided in order to keep the side castings properly spaced to form the top cross structure, a 90 screw 35 assisting in holding the castings together.

Rigidly secured to the upper end of the channel bar 5 of the side structure B is a casting E having the transverse passage-way 36 in which the end of a latch tongue 37 is pivoted by a pin 38. This latch tongue is flat and at its inner end has the upper and lower detent lugs 39 and 40 whose front ends are beveled in order that the tongue 110 may readily enter the upper cross structure C. To further facilitate entry the entrance

ends 25' and 26' are slightly flared. The spacing projections 32 and 33 are near the center of the upper cross structure and a U-shaped leaf spring 41 is secured at its base 5 to said spacing projections with its ends *a* and *b* deflecting outwardly to engage against the under side of the tongue to tend to hold the tongue up. The bolt 35 which serves to lock the side castings together and the lug 34' on the part 34, serve as stops for engaging with the upper detent lugs 39 and the lower lugs 40 on the tongue to prevent entire withdrawal of the tongue from the cross structure C, as clearly shown in Fig. 1. 10 At the opposite end of the cross structure the side castings have webs 42 and 43 extending from their upper edges and depending projections on said webs form a detent tooth 44 for coöperating with the upper detent lug 39 of the tongue to lock the tongue in its inner position, as shown in dotted lines Fig. 1, the tongue being held 20 yieldingly in its locking engagement with the tooth 44 by the spring 41. 25 When the tongue is in its innermost position in latching engagement with detent tooth 44 the side structures A and B are parallel. In order to readily break this latching engagement so that the side structure B can be swung out, a latch L is provided. This latch is pivoted at an intermediate point on a bolt or rivet 45 which extends through the upwardly extending ears 46 and 47 on the side castings 25 and 26. 30 Above the spring end *a* this latch has a rounded lug 48 on its under side, and an upwardly extending finger piece 49 by means of which the latch can be depressed to carry the lug 48 against the top of the tongue 40 when the tongue is in, such depression causing downward swing of the tongue against the upward pressure of the spring and release of the tongue detent lugs 39 from the detent tooth 44, and the side structure B can 45 then be swung out. The other end 50 of the latch is bent upwardly and rounded whereby this end may be readily raised by the finger to cause swing of the latch about its pivot and depression of the lug 48 against the latch tongue when it is in, the latch being 50 thus operable from either side of the stanchion without need of walking around the animal held to the stanchion. To assist in holding the side structures A and B together in closed position and to relieve the tongue from unnecessary strain the casting E has the upper projection 51 for engaging in the slot 52 in the latch L when the side structures are brought together. When the 55 latch is swung to release the tongue 37, the latch end 50 will be raised so that the projection 51 can readily leave the slot 52 to allow the structure B to be swung to open position. 60 In the lower cross structure B the side

castings have central spacing blocks 53 extending therefrom toward each other to form a cylindrical pocket 54 for a swivel connection or for receiving the end of a chain 55 anchored to a bolt or rivet 56 passing through the side castings. At the upper cross structure the projections 46 and 47 are semi-circular at the top to form a pocket 57 for swivel connection or for receiving the end of a chain 58 to be anchored by a bolt 75 59. By means of these chains the stanchion is secured to a suitable stanchion support running along the front of a stall or stalls. 70

I thus provide a very simple yet very efficient stanchion which can readily be adjusted to accommodate cattle of different sizes and in which the latch mechanism for locking the side structures in closed position can readily be released from either side of the stanchion. I do not, of course, desire 80 to be limited to the exact construction and arrangement shown as modifications are no doubt possible which would still come within the scope of the invention. 85

I claim as follows: 90

1. In a cattle stanchion, the combination with the frame side members and top and bottom members, one side member being hinged at its lower end, of a tongue extending from the upper end of said hinged side member and adapted to extend into said top member, an abutment within said top member, a spring tending to hold said tongue in locking engagement with said abutment, and a latch pivoted on said top frame member and operable from both sides of said stanchion to release said tongue from the abutment against the force of said spring, said latch having interlocking engagement with said hinged side member to 105 lock said side member in closed position independently of said tongue. 100

2. In a cattle stanchion, the combination with the frame side members and top and bottom members, one side member being hinged to the bottom member and the upper member being hollow, a locking tongue extending from said hinged member and adapted to enter said hollow top member and having a detent projection, an abutment within said hollow top member for coöperating with said detent projection to lock the hinged member in closed position, a latch pivoted on said top member and having an extension for coöperation with said tongue to effect disconnection of said tongue detent from the abutment and thereby release of the hinged member, said latch having an opening for receiving the upper end of said hinged member when said member is in closed position whereby said member is locked in closed position by the latch independently of said locking tongue. 110 115 120 125

3. In a cattle stanchion, the combination with the frame side members and top and 130

bottom members, one side member being hinged to the bottom member and the upper member being hollow, a locking tongue extending from said hinged member and 5 adapted to enter said hollow top member and having a detent projection, an abutment within said hollow top member for cooperating with said detent projection to lock the hinged member in closed position, a 10 latch pivoted on said top member and having an extension for cooperation with said tongue to effect disconnection of said tongue detent from the abutment and thereby release of the hinged member, said latch having 15 an opening for receiving the upper end of said hinged member when said member is in closed position whereby said member is locked in closed position by the latch independently of said locking tongue and so 20 arranged that when the latch is operated to release the tongue, the hinged member will be released from the opening in the latch. 4. In a cattle stanchion, the combination with side frame members and top and bottom frame members, one of said side members being hinged to the bottom member 25 and the top member being hollow, of a locking tongue pivoted on the hinged side member and adapted to extend into said top member, the end of said tongue being pro- 30

vided with a detent projection and said top frame being provided on the inside with an abutment, a spring acting against the under side of said tongue and tending to effect locking coöperation between said detent 25 projection and abutment when the hinged member is moved to closed position and the tongue shifted into the top member, a latch bar pivoted to said top member and having an extension adapted upon swing of said latch member to engage with the top of the tongue to effect depression thereof and disengagement of the detent projection from the abutment whereby to release the hinged member, said latch having an opening for 40 receiving the top of the hinged member when said hinged member is shifted to closed position whereby said hinged member is locked in closed position independently of said locking tongue, swing of said latch 45 member to release said locking tongue effecting also release of the latch from the hinged member.

In witness whereof I have hereunto set my hand and affixed my seal this 13th day 50 of April, A. D., 1915.

FRANK B. STRICKLER.
